Darrell F. Marquette[57] **CLAIM**

The ornamental design for a golf ball, as shown and described.

DESCRIPTION

FIG. 1 is a plan view of a golf ball embodying my new design taken in the direction of either one of two arrows designated "A" in FIG. 2; and,

FIG. 2 is a side elevational view of the golf ball shown in FIG. 1 taken in the direction of any one of four arrows designated "B" in FIG. 1.
